UNITED STATES PATENT OFFICE.

CHARLES SMITH, OF PROVIDENCE, RHODE ISLAND.

ADJUSTABLE SUPPORTING STANDARD FOR THE ATTRACTIVE DISPLAY OF FLORAL DESIGNS.

Application filed February 15, 1926. Serial No. 88,368.

My invention relates to means for supporting, mounted on wire frames, wreaths, pillows, crosses and other floral designs so as to display them in the most effective and attractive manner.

To this end my invention consists of the new and useful construction, combination and arrangement of parts hereinafter described and illustrated in the accompanying drawings, in which,

Figure 1 is a perspective view of my invention.

Figures 2, 3, and 4 are detailed views of certain parts of my adjustable supporting standard.

Figure 5 is a diagrammatic view showing a wreath supported by my invention for attractive display.

Figure 6 is a similar view showing a floral pillow similarly supported by my invention.

Like reference letters and numerals indicate like parts throughout the several views.

While I have shown in the drawings in outline only a floral wreath and a floral pillow as attractively supported by my invention, the latter may be as effectively utilized for the attractive support and display of floral crosses and other floral designs. When not in use for the described purpose my invention may be collapsed or folded into the form shown in Figure 4 in which form it may be conveniently shipped or packed away.

Referring to the drawings 1 represents one member of my invention which is provided with extensions 1¹ disposed at right angles to the main body of the member, 2 represents a similar member centrally pivoted on the first named member 1 and similarly provided with the extensions 2¹. Revoluble sleeves 3 carried on the upper ends of said sleeves are vertically slotted to thereby form oppositely disposed spring like extensions 4 adapted to clampingly engage a hook 5 pivotally mounted on said sleeve and adapted and arranged to hold the wire of the floral frame when the latter is seated in the transverse slot 6 in the upper end of the sleeve 4 and to be firmly locked in engagement with the wire of the frame by the clamping action of the parts 4 (Figs. 1, 2, 3, 4).

The pivotal connection of the members 1 and 2 enables the said extensions to be moved

toward or from each other to thereby readily adjust the distance between them to adapt my invention for the reception of differing sizes and shapes of wreath frames.

In the practical operation of my invention the members 1 and 2 are moved toward or from each other the proper distance to permit the insertion of the wire of the frame in the respective slots 6 to thereby dispose said frame in an inclined position on the standard. The hooks 5 are then inserted in the vertical slots between the clamping ends 4 and brought into engagement with the wire of the frame seated in the slots 6 to thereby hold the frame in an inclined position for attractive display on the standard, as illustrated in the diagrammatic view, Fig. 5. It will be noted that the standard serves as the sole supporting means for the floral design of any form.

I claim as my invention and desire to secure by Letters Patent:

1. The described means for supporting for attractive display floral designs mounted on a wire frame, the same consisting of two members centrally pivoted to each other, each member provided with angularly directed extensions, revoluble sleeves carried on the upper portion of said extensions, each said sleeve provided with oppositely disposed inwardly bent extensions, and transverse open slots disposed in the free end of the sleeve extensions and fitted for the seating therein of the wire of the frame of a floral design, a hook pivotally mounted on each revoluble sleeve and adapted for insertion at will between said sleeves extensions into engagement with the frame wire seated in said transverse slots and to be clampingly held by said sleeve extensions, all combined and arranged and adapted to serve as and for the purposes specified.

2. In supporting means for floral designs the combination with two conjointly pivoted members each provided with oppositely disposed angularly directed vertical extensions, of revoluble sleeves carried on said extensions and open slotted at their free ends and a hook pivotally mounted on each sleeve for insertion at will in said slots and clampingly held therein by the free ends of said sleeves.

CHARLES SMITH.
